UNITED STATES PATENT OFFICE

166,742

RUBBER SOLE FOR FOOTWEAR

Abraham C. Fellman, Forest Hills, N. Y.

Application December 14, 1951, Serial No. 17,726

Term of patent 14 years

(Cl. D7—5)

To all whom it may concern:

Be it known that I, Abraham C. Fellman, a citizen of the United States, residing at Forest Hills, State of New York, have invented a new, original, and ornamental Design for Rubber Sole for Footwear, of which the following is a specification, reference being had to the accompanying drawing, forming a part hereof.

Fig. 1 is a bottom plan view of a rubber sole for footwear, showing my new design.

Fig. 2 is a longitudinal sectional view taken on the line 2—2 of Fig. 1.

I claim:

The ornamental design for a rubber sole for footwear, as shown.

ABRAHAM C. FELLMAN.
